(57) **CLAIM**

The ornamental design for a bracket member, as shown and described.

DESCRIPTION

FIG. 1 is a front view of the bracket member of my new design;

FIG. 2 is a back view thereof;

FIG. 3 is a top view thereof;

FIG. 4 is a bottom view thereof;

FIG. 5 is a right view thereof;

FIG. 6 is a left view thereof;

FIG. 7 is a first perspective view thereof;

FIG. 8 is a second perspective view thereof; and,

FIG. 9 is an environmental view of the bracket member of the invention, in which the bracket member is used to join a furring strip to a wall face, and wherein the furring strip is also joined to an external wall member with a securing fixture.

The broken line showing of partial wall and structure is included for the purpose of illustrating environment and forms no part of the claimed design.
